TAPPET-LOCK FOR CONE BOXES IN A CONE-BAKING MACHINE

Garry G. Buttermann, Louisville, Ky.

Application December 20, 1938, Serial No. 246,904

1 Claim. (Cl. 107—58)

My invention relates to tappet-locks for metal cone-boxes adapted to open and close automatically in the course of a revolution of a rotary cone-baking machine; and one object of my invention is to prevent a sliding contact of the inner end of the tappet-lock against the tappet-cam, which, on account of the great pressure required to lock the cone-boxes tightly, formerly caused excessive friction between the inner end 10 of the tappet-lock and the long tappet-cam, designed to operate the lock, thus necessarily impeding the rotary movement of the cone-baking machine. Another object of my invention is to avoid the wearing away of the contacts parts, the inner end of the tappet-lock and the face of the tappet-cam over which the tappet-lock rides under severe pressure. Other objects of my invention will appear in the process of this specification.

The foregoing objects have been attained in the present invention; and my new and useful improvement in tappet-locks for cone-boxes in a cone-baking machine, illustrated in the accompanying drawing, forming a part of this specification, is a practical device embodying the aforesaid novel means and other new and useful details of construction, arrangement and combination of parts, all of which together with their functions will be described in detail with reference 20 to said drawing, and will be definitely pointed out in the claims that follow the description, so that any person skilled in the art may be able to construct and use this invention.

In said drawing, Fig. 1 is a side elevational view of one of the cone-boxes closed and locked and operative in a cone-baking machine, showing my improvement in tappet-locks holding the sides of the cone-box together. In this Fig. 1 is shown, also, a fragment of the cone-baking machine supporting the cone-box and the rocking tappet-cam controlling said lock.

Fig. 2 is a side-elevational view of said cone-box unlocked and open, showing the relative location of the tappet-lock and its operative cam 45 in their idle positions, and a fragment of the rotary cone-baking machine.

Fig. 3 is a front-elevational view of said cone-box and a side-elevational view of its operative tappet-cam, showing a slight upward incline at 50 the end thereof.

Fig. 4 is a side-elevational view of the rocking tappet-lock with its tappet-roller removed from the roller shaft thereof.

Fig. 5 is a side-elevational view of my tappet-

roller, showing the large circular opening at the center thereof.

Fig. 6 is an elevational view of the edge of said tappet-roller, showing the location of the circular roller-crown.

Fig. 7 is a side-elevational view of the internal bushing for said roller, showing the integral circular head thereon.

Fig. 8 is a side-elevational view of the circular head of said bushing, showing the circular boring 10 in the end thereof for installing on the round shaft of the inner end of the tappet-lock.

Fig. 9 is a side-elevational view of a fragment of said tappet-lock, showing the old type of the tappet at the inner end of said tappet-lock.

This invention has been designed and experimentally developed in its details of fabrication for the desirable purpose of avoiding a sliding contact of the inner end of the tappet-lock against the face of the long tappet-cam which 20 operates said tappet-lock in locking the cone-box; and also for the purpose of preventing the rapid wearing away of the impinging parts of the mechanism, the inner end of the tappet-lock and the face of the tappet-cam, in operating said 25 lock for locking the cone-box in normal service; for, to lock the cone-box securely requires great pressure exerted on the inner end of the tappet-lock. And with said purposes, as the special objects aforesaid, in view, I will describe my invention in detail, pointing out the new and useful features of the construction and the assembling of the individual parts and the combinations thereof, as illustrated in the drawing hereinabove 30 described, in which similar letters and characters refer to similar parts throughout the several views.

In the invention and development of my new and useful improvement in tappet-locks for cone-boxes in a cone-baking machine, I have thoroughly tested out every detail of the parts involved 40 in my complete improvement thereof in a year's experiment in actual service; and I have found my invention a complete success. And in the design and construction of my new improvement in tappet-locks for cone-boxes, I have turned down a predetermined part of the rectangular block 7 at the inner end of the old type of tappet-lock shown in Fig. 9, leaving a round shaft 3c of desirable size, standing out at right-angles 45 from the plane surface of the cut 3d of said rectangular block, as shown in Fig. 4. This round shaft 3c provided with a transverse hole near the end thereof for the insertion of a cotter-pin 5, is designed for the installation of my new 50 tappet-roller 4, combined loosely-fitting with the 55

internal bushing 4b, provided with the circular head 4c shown in Figs. 7 and 8. The circular roller 4 shown in Figs. 5 and 6, is provided with a circular crown 4a designed, in the service assembly of the parts, to fit loosely against said plane-surface cut as the base of the round shaft 3c, as shown in Figs. 1 and 2.

In assembling the new tappet-roller 4 for service on the shaft 3c at the inner end of said tappet-lock, we push the loosely-fitting bushing 4b into the large circular opening in the roller 4, so that the integral circular head 4c of the bushing 4b rests against the side of the roller 4 opposite the roller-crown 4a; and we then push this combination on over the round shaft 3c so that the roller-crown 4a will rest lightly against the plane-surface cut at the base of the shaft 3c. We then insert the cotter-pin 5 into the transverse hole near the end of the shaft 3c to hold this combination of roller and heavy, headed bushing, as a loose bearing thereof, in their operative position in normal service.

The primary object of the circular crown 4a on the tappet-roller 4 is to hold the tappet-roller 25 away from the great heat, of the inner end of the tappet-lock, running back by conveyance from the highly-heated cone-box 1 of the rotary baking machine, as the box passes through gas-flames in normal service; and the secondary object of said roller-crown is to reduce the friction 30 between the roller and the adjacent plane-surface cut 3c' as the roller 4 is rotated under great pressure in passing over the long face of the tappet-cam 6.

35 So, also, the large heavy bushing 4b with its integral circular head 4c, has been designed to fit loosely the hot shaft 3c and the roller 4, to help shield the roller from the high temperature of the shaft 3c and the inner end of the tappet-lock, and to furnish an internal rotary bearing for said roller in normal service. The tappet-lock 3 is prevented from side-tipping by means of the extension hub 3c' shown in Fig. 3.

In Fig. 1 the cone-box 1, provided with an 45 inner stationary side and an outer side adapted to swing on a pintle-hinge 1b, is shown closed and tightly locked with the tappet-lock 3, the outer hooked end of which is provided with a plane-beveled inner face 3a designed to press 50 the swinging side of said cone-box more tightly against the stationary side thereof, as the hooked end of the tappet-lock is forced down over the end of the bolt-catch shown in Fig. 1. This efficient locking pressure on the bolt-catch shown 55 in Fig. 1, is caused by the upward movement of the inner end of the tappet-lock 3 rocking over its pintle-hinge 3b as the tappet-roller 4 rides up over the tappet-cam 6, which, operated by the tappet-roller 4 at one end and by the 60 gravity weights 6c and the auxiliary weight 6c' at the other end, rocks up and down over its pintle-hinge 6b to lock the cone-boxes of the rotary cone-baking machine as they swing past the tappet-cam 6 supported by the upright stationary bracket 2a, a fragment of which is shown 65 in Figs. 1 and 2. To lock the cone-boxes securely, the ultimate pressure is put upon the tappet-lock as the tappet-roller passes over the secondary incline 6a of the tappet-cam 6, shown 70 in Fig. 3. These cone-boxes are unlocked for

delivering the baked cones along another arc of their circle of rotation, by means of a similar tappet-cam inverted, along the under side of which this tappet-roller passes to force the locking hook 3a from the bolt-catch on the cone-box 5 1, so that the swinging side of the box may be opened as shown in Fig. 2.

We can now clearly understand what a severe friction was generated formerly between the solid rectangular block 7 at the inner end of the old 10 type of tappet-lock on the cone-box and the stationary tappet-cam 6, in the operation of forcing the pressure for locking and unlocking these cone-boxes with a tappet-lock; and we can, also, fully understand the desirability, usefulness and efficiency of my new tappet-roller now installed on the inner end of the tappet-lock 3 for contacting the stationary tappet-cam 6, in the operation of locking and unlocking said cone-boxes. 20

Around the circular, rotary cone-baking machine these cone-boxes are arranged in series, each box being mounted on a separate radial arm extending out from the center of said machine, a fragment 2 of said arm being shown in Figs. 1 25 and 2 of the drawing.

In closing, I think I should add that in this description of my new and useful improvement in tappet-locks for cone-boxes in a cone-baking machine of the character described, it should be 30 well understood that the specific detail of the various parts of the instant embodiment of my present invention, as I have illustrated in the drawing thereof and fully described, are not to be considered as limitations in the construction 35 of my new improvement in tappet-locks for cone-boxes in a cone-baking machine; and that while keeping within the scope of my invention and claim, I may make desirable modifications in these details to facilitate quantity-production or 40 to economise in the fabrication of the parts thereof, provided I keep within the spirit of my invention. 45

Now, having thus described the various features and possibilities of my invention, the detail construction, arrangement and combination of its parts as well as their functions and the ways and means of assemblage, operation and application; these features and accessories of my new improvement in tappet-locks for cone-boxes, on 50 which I desire Letters Patent granted to me, I have set forth and specifically pointed out in the following claim:

I claim:

An improvement in a tappet-lock of the character described for locking cone-boxes in a rotary cone-baking machine provided with a stationary tappet-cam for operating said tappet-lock, said improvement comprising, a round shaft on the inner end of said tappet-lock; a heavy 55 bushing designed to fit loosely and rotatably on said shaft; a tappet-roller adapted to fit loosely and rotatably on said bushing; a circular head on the outer end of said bushing designed to rest lightly against said roller in rotation, to hold it 60 in place; and means for holding said parts in their service positions on said shaft in normal 65 operation.

GARRY G. BUTTERMANN.
